by Kerr, Page & Co., Attorneys.

UNITED STATES PATENT OFFICE.

JOSEPH C. HIGGINS, OF BOUND BROOK, NEW JERSEY.

SOFT-TREAD HORSESHOE.

SPECIFICATION forming part of Letters Patent No. 629,295, dated July 18, 1899.

Application filed April 26, 1899. Serial No. 714,496. (No model.)

To all whom it may concern:

Be it known that I, JOSEPH C. HIGGINS, a citizen of the United States, residing at Bound Brook, in the county of Somerset and State of New Jersey, have invented certain new and useful Improvements in Soft-Tread Horseshoes, of which I declare the following to be a full, clear, and exact description.

My invention relates particularly to that class of soft-tread horseshoes wherein the tread portion (which is composed usually of rubber) is of substantially the same shape and size as the metal shoe and is held in place against the shoe by a metal keeper, the arrangement being such that the keeper and rubber tread may be removed without the removal of the iron shoe from the horse's foot. Such construction is disclosed in an application heretofore filed by me, Serial No. 679,457.

My present invention is directed particularly to improvements in the metal keeper and in the means for securing it in place and preventing longitudinal or lateral displacement.

In the accompanying drawings, Figure 1 is a perspective of a horseshoe with my invention applied. Fig. 2 is a section upon the line 22 of Fig. 1, and Fig. 3 is a plan of the keeper detached.

A is a horseshoe of ordinary construction, except as to the particulars which I shall describe. To the lower or tread side of A, I apply a cushion B, of a rubber compound of suitable consistency or of other suitable material. Upon the lower side of the cushion B, which is cut out to receive it, I apply a keeper or auxiliary shoe C, which is preferably of the skeleton construction shown in Fig. 3, it being arranged to fit into depressions in the

surface of the cushion-tread B. This keeper C follows generally the contour of the main horseshoe A and is provided with nail seats or holes D, the main shoe being correspondingly perforated, these holes being arranged so that the horseshoe-nails x pass diagonally outward through the cushion B and emerge from the outer rim of the upper member A, where their points are turned over and clenched, as shown in Fig. 1.

The lower member or keeper C comprises a substantially flat body portion and has upon its upper side a projecting hook E near its forward end or toe and one or more feet, as

F F, near its rear end. The hook E is designed to engage with the hoof side of the main horseshoe A, as shown more particularly in Fig. 1, and the feet or projections F F contact with one or more projections G upon the heel or heels of the main shoe A. These depending projections E F, serve in connection with the nails x, to hold the plate C, and with it the cushion-pad B, in place, the projections E F acting particularly to resist displacement when the horse stumbles.

The advantages of construction which I have described are obvious, for by my invention the cushion-pad may be applied to a horseshoe or renewed without removing the main shoe A from the horse's foot, the only change necessary in the shoe A being the provision of outwardly-extending holes for the nails x and of slight projections G to contact with the feet F of the keeper.

The keeper C is of very simple construction. It may be stamped from sheet metal with the hook E and feet F in the same plane with the body C and afterward bent to the form shown. The particular form of C, so far as regards the cross pieces or braces I, is immaterial, such braces being provided as will give sufficient rigidity to the keeper. Any change in the braces I will of course necessitate corresponding changes in the depressions upon the lower or tread side of the cushion-pad B.

I do not intend to limit myself to the details of construction shown, as the form, arrangement, and mode of attachment of the several parts may be varied considerably within the spirit of my invention. It may also be applied to horseshoes of other shapes than the one illustrated—as, for example, to the well-known bar-shoe.

What I claim as my invention is—

In a soft-tread horseshoe, the combination of a main metal shoe, a cushion-pad of substantially the same contour as the shoe, and a keeper designed to fit into depressions in the surface of the cushion-pad and provided with projections designed to contact with the main metal shoe, substantially as and for the purposes described.

JOSEPH C. HIGGINS.
